UNITED STATES PATENT OFFICE.

ALBERT R. TIFFANY, OF DAYTON, OHIO, ASSIGNOR OF ONE-HALF TO WESLEY YOUNG, OF SAME PLACE.

TAG-WIRING MACHINE.

SPECIFICATION forming part of Letters Patent No. 444,403, dated January 6, 1891.

Application filed July 9, 1890. Serial No. 358,196. (No model.)

To all whom it may concern:

Be it known that I, ALBERT R. TIFFANY, a citizen of the United States, and a resident of Dayton, in the county of Montgomery and State of Ohio, have invented certain new and useful Improvements in Tag-Wiring Machines, of which the following is a specification.

The object of my invention is primarily to twist wire around nursery-tags, and the machine is constructed so as to automatically feed the tag, wire it, and throw it out in consecutive time movements.

The various features of my invention will be fully set forth in the description of the accompanying drawings, making a part of this specification, in which—

Figure 1 is a top plan view of my improved machine. Fig. 2 is an end elevation. Fig. 3 is a section on line xx , Fig. 1. Fig. 4 is a detail view of the wire-feeding jaws. Fig. 5 is an end view of the twister-head. Fig. 6 is a section on line zz , Fig. 5. Fig. 7 is a section on line yy , Fig. 1. Fig. 8 is a detail view of the twisting mechanism. Fig. 9 is a detail view of the feeding-fork. Fig. 10 is a plan view of one of the cams. Fig. 11 is a plan view of the wired tag.

H represents the frame of the machine. I represents the wire-spool holder, on which the wire is wound to be employed in wiring the tags.

J represents an upright tag-holding hopper in which the tags a are stacked. They are fed down by gravity to the tag-feeding shaft L.

M represents the main driving-shaft; N, the pulley.

All of the operations of the machine are performed by a series of cams A B C D E F G, properly secured on said shaft. Cam A operates the sliding shaft 1 by means of the friction-roller 2. To reciprocate said shaft forward I have shown a spring 4, adapted to hold the friction-roller 2 in contact with the cam for the back motion. A close cam could, however, be employed in lieu of the spring.

3 represents a bell-crank lever hinged to the frame by center 5, provided with slots 6 and 7, which engage, respectively, over the crank-pins 8 and 9. When said shaft 1 is fed forward, the bell-crank lever moves the feed-

ing-slide L forward and carries the tag a into the position shown at a' , Fig. 1.

10 represents a spring-finger, which bears upon the tag a and holds it in position for 55 wiring. The wire P is fed from the pulley I around pulley Q and up through the hollow mandrel 11. (See Fig. 2.)

12 and 13 represent feeding-jaws, which slide vertically on the ways 14. (See Figs. 3 60 and 4.)

The jaws are operated as follows: Cam F is provided with a groove f , in which frictional roller 15 travels. Said roller is journaled to the arm 16, which is slotted to slide freely 65 over the main shaft M. 17 represents a connecting-rod journaled to the lower end of said arm and to the center 18 upon the bracket 19. To the forward end of the arm 17 is journaled a pitman 20, which is likewise hinged to the 70 movable jaw 13, which pivots upon the center 21. As this pitman is raised up the force applied to the jaw 13 holds it firmly against the jaws 12. When the jaws 12 and 13 are in their position, they straddle the end of the wire P, 75 which is in position shown in Figs. 2 and 3. As the cam F revolves to raise the pitman up, the jaws, being drawn together, grasp the wire and pull it up, the elevated position of the jaws being shown in Fig. 2. At this point the 80 cam D on said shaft M has moved around and come in contact with the stud-roller 23, which is journaled on the bracket 24, to which is attached a shank 25, carrying the knife-point 26, which cuts off the wire against the top of 85 the hollow mandrel. As soon as the wire is cut off, the cam C feeds the looping-fork R forward. The forward end of said fork is provided with a groove r to catch the wire and hold it from lateral movement. The said 90 looping-fork is driven by the cam C and its engagement with the friction-roller 27 on the shank of the feeding-fork R. Said shank is slotted at its rear end at 28, so as to slide freely over the main shaft M. 95

S represents a twisting-head, which is journaled in the bracket 68. It is provided with an opening 29, sufficiently large for said looping-fork to pass freely through. Said feeding-fork passes sufficiently through the twisting-head, so as to be opposite the holding-pin 100 30, (shown in Figs. 1 and 3,) and it arrives in

this position just in advance of the forward feeding movement of the tag *a*, so that the tag is fed through the slot *R'* of the loop-fork. This forward movement of the fork catches 5 the wire and doubles it over, extending longitudinally across said fork, as shown in Fig. 9. (See also Fig. 3.)

In order to prevent the wire from being displaced by the retreat of the looping-fork, a 10 holding mechanism is provided, which consists of the holder 30, which is tapped through the lever 31, which is secured to the rock-shaft 32, and the finger 33 is likewise secured to said rock-shaft, and it is operated by means 15 of the cam *G*, friction-roller *G'*, and feeding-shaft *g*, so that the wire-holder 30 may be brought in contact with the wire just before the looping-fork is withdrawn. The rock-shaft is brought back into position by 20 means of the spring 34 when the cam *G* has ceased to operate said rock-shaft. The looping-fork *R* is retracted by the cam *C*, leaving the wire in place over the tag *a* ready to be 25 twisted by the twisting-head *S*. On said twisting-head is a beveled pinion 35, driven by the bevel-pinion 36, which bevel-pinion is driven by means of the spur-wheel 37, secured to the shaft 38, on which the bevel-gear is mounted, and the rack-bar 39, which is attached to the slotted shank 40. (See Figs. 3 and 8.)

41 represents a friction-roller journaled on the shank 40 of the rack-bar, which travels in the groove 42^a of the cam *B*, which drives the rack-bar 39 forward and revolves the twisting-head to twist the wire at the appropriate time. This twisting is accomplished by means of clamp-jaws 42 43, which are pivoted to the twisting-head *S*, and are operated 35 by means of the sliding ring 44, which is gimbaled to the jaws 45 of the arm 46. Said arm and ring are moved laterally by means of shaft 47, cam *E*, and friction-roller 48. In Fig. 6 I have shown the ring in its forward 40 position grasping the free ends of the wire around the tag *a*. While the jaws 42 43 are clamped upon the wire in this position the twisting-head *S* is revolved by the bevel-gear 35 and 36, as above described. When the 45 wiring of the tag is completed, the recoil of the spring 49 draws the ring 44 backward and releases the jaws 42 43 for the next forward movement of the looping-fork. The cam *A* then moves a second tag *a* forward, which engages with the tag already wired and moves it forward until said wired tag drops out. The 50 cam *A* slows up at this point and the fork *R* is thrust forward, carrying the wire into position, when the cam *A* again moves in the proper direction to force the tag in the fork. Thus the operation of the machine is continuous and in time movements.

50 represents a spring attached to the pitman 17 to assist in pulling the feeding-jaws 12 down; but when a closed cam *F* is employed 65 the spring may be omitted.

51 represents a spring coiled around the shaft *g* for retracting the wire-holder 30 at the appropriate time before the second tag is placed forward for wiring.

Having described my invention, what I claim is—

1. In a tag-wiring machine, in combination with the wire feeding and cutting mechanism, the looping-fork *R* and the hollow twisting-head *S*, and the mechanism for reciprocating said looping-fork to place the wire around the tag, substantially as described. 75

2. In a tag-wiring machine, the combination of the reciprocating looping-fork *R* with the wire-feeding mechanism, consisting, substantially, of the jaws 12 and 13, operated by the pitman 20 and driving mechanism from the main shaft, whereby the wire is grasped and pulled forward into position in front of the 85 looping-fork *R*, substantially as specified.

3. In a tag-wiring machine, the reciprocating looping-fork *R*, in combination with the jaws 12 and 13 and mechanism for reciprocating the same, the cutting-knife 26, and the 90 mechanism for reciprocating the same at the end of the stroke of the feeding-jaws, substantially as specified.

4. In a tag-wiring machine, the combination of the looping-fork *R* and the mechanism for reciprocating the same, the hollow twisting-head *S*, with the cam-jaws 42 and 43, and the mechanism for operating said looping-fork to feed the wire forward over the tag, and the mechanism for clamping the jaws 42 and 43 100 for twisting the wire by a revolution of the head *S* and looping-fork *R*, substantially as herein set forth. 95

5. In a tag-wiring machine, the combination of an upright hopper *J* for containing a stack 105 of superimposed tags, a reciprocating slide *L*, moving beneath the hopper and acting to engage and move a tag forward from the lower end of the hopper, the reciprocating looping-fork *R* for catching the wire, the hollow twisting-head *S*, through which the looping-fork passes, the wire-feeding jaws 12 and 13, and operating mechanism, substantially as described. 110

6. In a tag-wiring machine, the combination 115 of an upright hopper *J* for containing a stack of superimposed tags, the slide *L*, moving beneath the hopper and acting to engage and move a tag forward from the lower end of the hopper, the looping-fork *R*, the hollow twisting-head *S*, and means for reciprocating the slide and looping-fork and rotating the twisting-head, substantially as described. 120

7. In a tag-wiring machine, the hollow twisting-head *S*, provided with vibrating jaws 42 125 and 43, a clamp-ring 44, and the mechanism for moving the clamping-ring and driving the twisting-head, substantially as specified.

8. In a tag-wiring machine, the combination of the reciprocating looping-fork *R*, provided 130 with an eye for receiving and holding the slat, with the wire-holder 30 and mechanism for

reciprocating the latter to engage and hold the wire fed forward by the looping-fork, substantially as described.

9. In a tag-wiring machine, the combination of the looping-fork R, provided with an eye for receiving and holding the slat, with means for moving the fork forward to carry the wire over the tag, substantially as described.

10. In a tag-wiring machine, the combination, with the twisting mechanism, of the re-

ciprocating fork R, provided with an eye in rear of its slotted or forked portion for receiving and holding the slat which is passed through said eye, substantially as described.

In testimony whereof I have hereunto set my hand.

ALBERT R. TIFFANY.
